(57) **CLAIM**

The ornamental design for a caravan as shown and described.

DESCRIPTION

1. Caravan
2. Caravan
6. Caravan
- 1.1 : Back
- 1.2 : Perspective
- 1.3 : Front
- 1.4 : Right
- 1.5 : Perspective
- 1.6 : Left
- 1.7 : Top
- 2.1 : Back
- 2.2 : Front
- 2.3 : Right
- 2.4 : Left
- 2.5 : Top
- 6.1 : Perspective
- 6.2 : Left
- 6.3 : Right
- 6.4 : Back
- 6.5 : Perspective
- 6.6 : Front
- 6.7 : Top

The design shows a caravan for camping. The stippling shown in reproductions 6.1-6.7 indicates a contrast in

(Continued)

appearance. The dashed broken lines depict portions of the caravan that form no part of the claimed design.

1 Claim, 19 Drawing Sheets
